United States Patent Office

Des. 208,993
Patented Oct. 24, 1967

208,993

GARDEN CULTIVATOR

Howard A. Anderson, Pittsburgh, Pa., and Henry J. Rosendall, Grand Rapids, Mich., assignors to Bissell Inc., Grand Rapids, Mich., a corporation of Michigan

Filed Aug. 24, 1966, Ser. No. 3,577

Term of patent 14 years

(Cl. D35—2)

FIG.1

FIG.2

FIG.3

FIGURE 1 is a side elevation of a garden cultivator, showing the new design, the opposite side being a mirror image;

FIG. 2 is a top plan view thereof; and
FIG. 3 is a front elevation thereof.

We claim:

The ornamental design for a garden cultivator, substantially as shown and described.
